UNITED STATES PATENT OFFICE.

LEWIS MOORE, OF JOLIET, ILLINOIS, ASSIGNOR TO MOORE BROTHERS COMPANY, OF JOLIET, ILLINOIS, A CORPORATION OF ILLINOIS.

DESIGN FOR A STOVE.

51,605.

Specification for Design.

Patented Dec. 18, 1917.

Application filed August 2, 1915. Serial No. 43,333. Term of patent 14 years.

To all whom it may concern:

Be it known that I, LEWIS MOORE, a citizen of the United States, residing at Joliet, Will county, Illinois, have invented a new, original, and ornamental Design for Stoves, of which the following is a specification.

The figure on the drawing forming a part of this specification is a perspective view of a stove made in accordance with my present invention.

The purpose of this invention is to provide a new and ornamental design which will affect the general appearance of the stove made in accordance with the design as well as its several parts.

Viewing the drawing it will be noted that the stove shown thereon has the usual base 1 of full rounded curves. Above the base the lower portion of the stove or the part containing the ash pit is formed of four upwardly and thence inwardly curving walls 2 above which is the fire box 3 the lower portion of which only appears on the drawing.

The upper part of the stove is contained within a casing or jacket 4 defined by walls of general rectangular configuration. These walls however are not wholly flat but wave out at the bottom at 5 and at the top at 6. The bottoms 5 are waved across the stove and the edges of the generally rectangular walls meet in curved surfaces 7. The top 6 of the walls are curved upwardly and outwardly from end to end and they are surmounted by two domes 8 and 9 of general rectangular cross sectional shape. The corners are rounded. The general effect of the stove is of rectangular structure with the softer effect of a round or cylindrical one.

I claim:

The ornamental design for a stove as shown and described.

LEWIS MOORE.
